UNITED STATES PATENT OFFICE.

MILLARD BURGESS ANDRUS, OF DRAPER, UTAH.

BEET TOPPER.

Application filed April 6, 1922. Serial No. 550,075.

To all whom it may concern:

Be it known that I, MILLARD B. ANDRUS, a citizen of the United States, residing at Draper, in the county of Salt Lake and State 5 of Utah, have invented certain new and useful Improvements in Beet Toppers; and I do declare the following to be a full, clear, and exact description of the invention, such as will enable others skilled in the art to 10 which it appertains to make and use the same.

This invention relates to an improved beet pulling and topping machine and one 15 object of the invention is to provide a machine of the character described which is so constructed that it may be hitched behind a conventional structure of beet lifter which serves to loosen and lift the beets from the ground, the machine forming the 20 subject matter of this invention serving to remove the loosened and partially lifted beets from the ground and cut the beet tops from the roots.

Another object of the invention is to provide an improved type of beet holding means 25 which consists of a rotating wheel device having arms between which the beets are to be grasped and held while the tops are removed, each set of these arms further serving to actuate means for pressing a beet into firm engagement with another set of arms.

Another object of the invention is to so construct this machine that each set of gripping arms may carry a knife for removing 30 the beet tops, these knives being brought into engagement with a cam element as the wheel rotates and when in engagement with the cam element being moved to slice the beet root and thus remove the top.

Another object of the invention is to provide improved means for removing the beet roots from the arms as the wheel rotates.

Another object of the invention is to provide a beet puller and topper which will 45 operate very efficiently and will not be liable to readily get out of order.

This invention is illustrated in the accompanying drawings, wherein:

Figure 1 is a top plan view of the improved beet topper.

Figure 2 is a longitudinal sectional view through the same.

Figure 3 is a transverse sectional view taken along the line 3—3 of Fig. 1 and 55 looking towards the rear end of the machine.

Figure 4 is a sectional view taken along the line 4—4 of Fig. 1, looking forwardly.

Figure 5 is a transverse sectional view through the forward end portion of the machine taken along the line 5—5 of Fig. 1. 60

Figure 6 is a sectional view taken along the line 6—6 of Fig. 1.

Figure 7 is a transverse sectional view taken along the line 7—7 of Fig. 1.

Figure 8 is a longitudinal sectional view 65 taken along the line 8—8 of Fig. 2.

This improved beet topping machine is to be connected at the rear of a conventional structure of beet lifter and is intended to receive the beets after they have been lifted 70 from the ground by the beet lifter and after removing the tops from the roots, drop the roots upon the ground or into a suitable receptacle which may be provided at the rear of the machine if so desired. This improved 75 machine is provided with a frame having side bars 1 and end bars 2 and 3. The end bars 2 and 3 carry strips 4 and 5 which extend longitudinally of the frame and the side bars 1 carry bearings 6 so that the axle 80 7 which may be termed a main drive shaft may be rotatably mounted with the axle extending transversely of the frame and having its end portions extending beyond the sides thereof to carry supporting wheels 85 8. The axle will turn with the wheels when moving forwardly, it being understood that if desired a conventional structure of pawl and ratchet may be provided so that a turn may be readily made. A driven shaft 9 is 90 rotatably mounted in bearings 10 carried by the strip 4 and one of the side bars 1 and carries a sprocket wheel 11 about which passes a sprocket chain 12 moved by means of a sprocket wheel 13 carried by the main drive shaft or axle 7. This driven shaft 9 carries a relatively large gear wheel 14 which meshes with a smaller gear wheel 15 loosely mounted upon the axle 7. This small gear wheel 15 is provided with openings through which extend bolts 16 which pass through a hub disk 17 forming part of the beet holding wheel. Sleeves 18 are mounted upon the bolts 16 between the hub disk 17 and the sprocket wheel 13 so that 105 the gear 15 will be held in spaced relation to the beet holding wheel and in proper position for meshing with the large gear wheel 14. Upon the opposite side of the hub disk 17 there has been provided a sleeve 110

19 which fits loosely upon the axle 7 between the hub disk and a sprocket wheel 20 which is rigidly connected with the shaft. It will thus be seen that when the machine is moving forwardly, the shaft 7 and sprocket wheel 20 will turn in one direction, whereas the gear 15 and hub disk 17 will turn in an opposite direction and the beet holding wheel be thus caused to turn rearwardly instead of forwardly.

This beet carrying wheel is provided with radiating arms 21 and 22 which are formed of resilient material and have their inner ends secured to the hub disk and have their outer end portions extending in diverging relation as clearly shown in Fig. 3. Each of the arms 21 carries a knife blade 23 which is pivotally connected with a bearing bracket 24 and is engaged by a spring 25 carried by an eye-bolt 26 which passes through the hub disk 17. Abutments 27 are provided for engaging the cutting knives and limiting their swinging movement under action of the springs. It is desired to have these knives swung from the inoperative position shown in the lower portion of Fig. 3 to the operative position shown at the upper portion of this figure, as the beet-carrying wheels rotate rearwardly and thus permit the tops to be cut from the roots of the beets. In order to do so, there has been provided a cam plate 28 which is secured upon the strip 5 and is provided with a curved upper end portion which will be engaged by the knives as the wheel rotates and will serve to swing the knives against the action of the springs 25. As soon as the knives move out of engagement with the cam plate, the springs will return them to the inoperative position.

In order to carry the beets rearwardly into position for engagement by the arms 21 and 22, there have been provided endless conveyors 29 and 29' which pass about the rollers 30 and 31, the rollers 31 being carried by shafts 32 and 32' which extend upwardly and carry gears 33 and 33' meshing with gears 34 and 34' carried by a shaft 35. This shaft 35 is mounted in bearings 36 carried by the strips 4 and 5 and carries a sprocket wheel 37 about which passes a sprocket chain 38. This sprocket chain 38 passes around the sprocket wheel 20 and it will therefore be seen that the shaft 35 will be rotated from the axle when the machine is in motion. The shaft 32 passes through bearing arms 39 of a hanger bracket 40 secured to the strip 4 and the other shaft 32' has its lower end portion positioned in a slot formed in a bearing arm 41 at the lower end of a hanger bracket 42. This bracket 42 is provided with an upper bearing arm 43 having a slot formed therein in which is mounted a bearing 44 through which the shaft 32' of this conveyor extends. It will

thus be seen that this shaft 32' may have movement towards and away from the other shaft. The gear 34' with which the gear 33' of this shaft meshes is keyed upon the shaft 35 for sliding movement and is held in engagement with its co-operating gear 33' by means of a bracket 45. Brackets 46 are mounted upon the shafts 32 and 32' and carry arms 47 which extend forwardly in diverging relation. The bracket 46 which is mounted upon the shaft 32' carries rods 48 which extend through openings formed in the hanger bracket 42 and carry springs 49 which engage the hanger bracket and serve to yieldably retain the forward end portion of the endless conveyor 29' against movement away from the conveyor 29. The rollers 30 at the rear ends of the conveyors 29 and 29' are provided with shafts 50 and 50', the shaft 50 being journaled in the arms 51 of the hanger bracket 52 carried by the strip 4 and the shaft 50' having its end portion rotatably and slidably carried by the arm 53 of the hanger bracket 54. Brackets 55 which are similar to the brackets 46 are carried by these shafts 50 and 50' and carry a rearwardly extending V-shaped spreader 56 which is however directly secured to rearwardly extending arms 57 of the brackets. Rods 58 extend from the bracket mounted upon the shaft 50' and extend through openings formed in the hanger bracket 54. Springs 59 are carried by these rods 58 and serve to yieldably retain the rear end portion of the conveyor 29' against movement away from the rear end portion of the conveyor 29. From an inspection of Fig. 2, it will be readily seen that as the beet carrying wheel rotates, the beet engaging arms 21 and 22 will engage the spreader 56 as they move upwardly and the arms will thus be spread apart so that the beets which are moving rearwardly can be forced into firm position between these arms. As soon as the arms move out of engagement with the spreader, they will tend to return to their normal position with respect to each other and the beets will thus be very firmly gripped.

When the beets are to be brought into position between the gripping arms, they must be thrust between these arms and before they can be thrust between the arms, they must be moved between the strips 57. There has therefore been provided a lever 60 which is pivotally mounted by a shaft 61 carried by bearing brackets 62 which extend upwardly from the strips 4 and 5. This lever is curved as shown in Fig. 2 and has its lower end portion provided with a hasp 63 to rotatably carry a roller 64. The upper end portion is provided with a cross bar 65 for engagement by the arms 21 and 22 and this cross bar carries a stem 66 which extends forwardly through an opening formed

in a cross strip 67 and carries a spring 68. This spring 68 which will serve to normally retain the lever in a set position with the roller in position to engage the beets when they leave the rear ends of the conveyors 29 and 29'. As the wheel turns, the arms which have passed out of engagement with the spreader and have a beet root clamped between them, will engage the cross-bar 65 and will swing the lever 60 so that the lower end portion thereof will be swung rearwardly. The roller will engage a beet which by this time will have moved out of position between the upper ends of the 10 endless conveyors 29 and 29' and this beet will be forced rearwardly between the strips 57 until the beet reaches the ends of the strips. In the meantime, the arms below those which engage the cross bar 65 will have moved upwardly and will be spread apart so that as the wheel continues to rotate, the lever may force the beets into position between the arms 21 and 22 and then move out of engagement with the beets. 15 The arms which are engaging the cross bar of the lever will then move out of engagement with this cross-bar and the spring will return the lever to the normal position. The arms between which the roller has been forcing the beets, will by this time have moved into tight gripping engagement with the beets and the beet root will be held in the position shown in Fig. 2 in operative relation to the cutting knife so that when the 20 cutting knife is swung by the cam to the operative position, the beet tops will be severed from the roots. After the beet top has been removed from the root, it will drop upon the ground but the root will be held by the 25 arms until the arms move upon opposite sides of the tapered removing element at the rear end of the main frame of the beet topper. This beet removing device which is indicated in general by the numeral 69 is 30 provided with strips 70 which extend rearwardly in diverging relation as shown in Fig. 1 and have their ends rigidly mounted upon a rod 71 between spacing sleeves 72. This rod 71 is carried by hanger bars 73 secured to the rear bar 2 of the main frame beneath the strips 4 and 5. It will thus be seen that the beets after being lifted from the ground by the conventional structure of beet lifter may be guided between the forwardly extending arms 47 into position for engagement by the endless conveyors and by these endless conveyors carried rearwardly into position for engagement by the lever 60 which will force the beets rearwardly into position between the arms of the beet carrying wheel so that this wheel may carry the beets upwardly and rearwardly into positions to have the tops removed and then downwardly into position for engagement by the removing device 69

which will remove the beets from between the arms 21 and 22 and permit them to roll rearwardly and drop upon the ground or into a suitable receptacle which may be provided if so desired.

70

I claim:

1. A beet topper comprising a frame, endless conveyors for receiving beets from the ground and carrying the beets rearwardly, spaced strips extending rearwardly from the rear ends of the conveyors a spreader carried by said strips, a beet carrier wheel rotatably mounted and having sets of resilient arms moved away from each other by the spreader as the wheel rotates, means actuated by said wheel for forcing beets from the conveyors between the strips and into position between spread arms of the wheel, cutting blades carried by the wheel adjacent the arms, cam means for moving the blades 80 to cut the beet tops from the roots as the wheel rotates, and means for removing the beet roots from between the arms as the wheel rotates.

85

2. A beet topper comprising a frame, means for receiving untopped beets and directing the beets rearwardly, a beet carrier wheel rotatably mounted and having sets of resilient beet gripping arms movable transversely of the wheel, means for spreading the arms as the wheel rotates, means actuated by each set of arms for thrusting beets into position between a following set of arms while the last mentioned arms are spread, cutting means for removing beet tops while the roots are gripped between the arms, and means for removing beet roots from between the arms after the tops have been removed.

95

3. A beet topper comprising a frame, means for receiving untopped beets and directing the beets rearwardly, a beet carrier wheel rotatably mounted and having sets of resilient beet gripping arms movable transversely of the wheel, means for spreading the arms as the wheel rotates, means for thrusting beets from the beet receiving means into position between the arms while the arms are held spread, cutting means carried by said wheel for removing beet tops 105 from the roots as the wheel rotates, and means for removing beet roots from between the arms as the wheel rotates.

110

4. A beet topper comprising a frame, means for receiving untopped beets, a beet carrier wheel rotatably mounted and having resilient arms extending radially in pairs for gripping beets, means for thrusting beets from the receiving means into position between the arms, a cutting blade 120 pivotally connected with one arm of each set, a cam for moving the blades to cut the beet tops from the roots as the wheel rotates, and means for removing the beet roots 125 from between the arms.

130

5. The structure of claim 2 having the means for thrusting the beets into place between the arms consisting of a lever vertically disposed and pivotally mounted and 5 having at its lower end a beet engaging roller, the upper end portion being bent and extending rearwardly and terminating in a cross head for engagement by the arms of the beet carrying wheel, and resilient 10 means yieldably holding the lever against movement by the wheel.

6. A beet topper comprising a frame, means for receiving beets from the ground and conveying the beets rearwardly, said 15 means consisting of endless belts positioned longitudinally of the frame in a vertical plane and spaced apart transversely of the frame, forward and rear rollers for each endless belt rotatably mounted and the rollers 20 for one belt being slidably mounted for movement towards and away from the other belt and yieldably held against movement away from the same, a driven shaft having operative connection with the rollers, a drive 25 shaft, a beet carrying wheel upon the drive shaft, means for transmitting rotary movement from the drive shaft to the driven shaft, means moving the beets from the conveyor means into engagement with said 30 wheel, means for removing the beets from the wheel after the tops are removed.

7. A beet topper comprising a frame, means for receiving beets from the ground and conveying the beets rearwardly, a drive

shaft, a beet carrying wheel having a hub 35 loose upon the shaft, resilient arms radiating from the hub in pairs, means for moving beets from the beet conveying means into engagement with the resilient arms, a gear wheel loose upon said shaft connected 40 with said hub to one side thereof, a gear rigid upon the shaft, a gear rotatably mounted and meshing with the gear carried by the hub, a gear to one side of the last mentioned gear and rigid therewith and 45 meshing with the gear rigid upon the drive shaft, a cam carried by said frame, knife blades pivotally carried by certain of said arms and moved to an operative position when engaged with said cam, and a root receiving structure having a tapered end portion 50 extending to engage beets and remove the beets from the arms as the wheel rotates.

8. A beet topper comprising a frame, means for receiving untopped beets, a carrier wheel rotatably mounted and having resilient arms for gripping beets, means for thrusting beets from the receiving means into position between the arms, cutting means carried by the wheel for removing the beet tops from the roots as the wheel rotates, and means for removing roots from between the arms after the tops have been removed.

In testimony whereof I have hereunto set 65 my hand.

MILLARD BURGESS ANDRUS.
